UNITED STATES PATENT OFFICE

CRUSE W. MOSS, OF KENT, OHIO, ASSIGNOR TO THE GOODYEAR TIRE & RUBBER COMPANY, OF AKRON, OHIO, A CORPORATION OF OHIO

DESIGN FOR A TIRE

Application filed June 18, 1931. Serial No. 40,265. Term of patent 14 years.

To all whom it may concern:

Be it known that I, CRUSE W. Moss, a citizen of United States, residing at Kent, in the county of Portage and State of Ohio, have invented a new, original, and ornamental Design for a Tire, of which the following is a specification, reference being had to the accompanying drawings, forming part thereof.

Fig. 1 is a perspective view of a tire with sidewall portions in full lines showing my new design,

Fig. 2 is a fragmentary side elevation, on a larger scale, with sidewall portions in full lines,

Fig. 3 is a fragmentary cross-sectional view taken on line III—III of Fig. 2,

Fig. 4 is a fragmentary cross-sectional view taken on line IV—IV of Fig. 2.

I claim:

The ornamental design for a tire, as shown.

CRUSE W. MOSS.
